UNITED STATES PATENT OFFICE.

ROBERT GALBRAITH RUSSELL, OF BURGETTSTOWN, PENNSYLVANIA.

CARBURETOR-CHOKER CONTROL.

Application filed November 4, 1927. Serial No. 231,138.

This invention relates to a carburetor choker control, the general object of the invention being to provide automatic means for controlling the opening movement of the choker valve in such a manner as to secure the most efficient results at the starting of an internal combustion engine by giving it the proper mixture from the starting of the motor to the point where it is running under normal conditions.

Another object of the invention is to so arrange the parts that the atmospheric temperature will regulate the operation of the device so that the colder the day, the longer the choker will take to close and vice versa.

Another object of the invention is to provide means for adjusting the parts to set them at the most efficient points.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a diagrammatic sectional view showing the invention applied to the choker of a motor vehicle.

Figure 2 is a section on line 2—2 of Figure 1.

Figure 3 is a section on line 3—3 of Figure 2.

Figure 4 is a detail view showing the adjusting means for the lower spring.

In these views, the numeral 1 indicates a cylinder which has its lower end closed and to which is connected a rod 3, the hooked end of which is connected with the arm 4 of the choker valve. The upper end of the cylinder is closed by a cap 5 and a plug 6 is associated with this end of the cylinder so that oil or the like can be placed in the cylinder. A perforated ear 7 projects from the under side of the top part of the cylinder and a rod 8 passes through the perforation in this ear and through the dash 9 and instrument board 10 of the vehicle. Nuts 11 are threaded on the lower end of the rod and a spring 12 is placed on the upper end of the rod between the instrument board and a projection 13 on said

rod and tends to hold the rod with its knob 14 against the instrument board. 55

An elongated hollow piston 15 is arranged in the cylinder with its upper end pointed and fastened to a piston rod 16 which passes through the cap 5 and through a hole in the bracket 17 attached to the dash. A pair of nuts 18 is threaded to the upper end of the piston rod to one side of the bracket and a second pair of nuts 19 is threaded to the rod on the opposite side of the bracket so that by adjusting the two pairs of nuts, the amount of movement of the rod and piston can be regulated. Perforations 20 are formed in the upper pointed end of the piston and an opening 21 is formed in the lower end thereof, this latter opening being controlled by a ball valve 22 which opens inwardly. 65

From the foregoing it will be seen that by pulling upon the knob 14 of the rod 8, the nuts 11, striking the ear 7, will cause the cylinder 1 to move with the rod and as said cylinder is attached to the choke valve, said valve will be closed if the choker rod 8 is moved upwardly or outwardly to its full extent. On the first part of the upward movement of the cylinder 1, the piston 15 and its rod 16 will move with the cylinder and as soon as the nuts 18 strike the brackets 17, further movement of the piston and its rod will be prevented. Then upward movement of the cylinder 1 will cause the oil in its lower part to raise the valve 22 off its seat and the oil 75 will pass through the piston and through the perforations 20 in the upper end of the piston into the upper part of the cylinder. After the motor has started, the choker is released and the spring 12 will return the rod 8 to its normal position, the rod simply passing through the perforation in the ear 7 during this movement. 80

A spring 23 has one end attached to the closed end of the cylinder 1 and its other end 95 is adjustably connected with a part of the carburetor, and as soon as the choker rod is released, this spring tends to move the cylinder 1 downwardly or to a position where the choker valve will be opened. This spring 100 will move the parts downwardly quickly until the nuts 19 on the piston rod strike the bracket 17, when further movement of the piston 15 will be prevented and said piston, with the oil in the cylinder, will check the 105 downward movement of the cylinder under

the action of the spring 23, as a vacuum will be created in the lower part of the cylinder by the piston, which vacuum is slowly broken by the oil in the top of the cylinder passing by the piston and entering the lower part of the cylinder. This oil cannot pass through the piston on account of the check valve 22. Thus the choker valve will be opened to a slight extent very quickly after the choker rod is released, but then the opening movement of the choker valve will be retarded by the action of the cylinder and the piston. Thus the engine will have time to pick up before the choker valve reaches fully open position. As will be seen, the device is arranged close to the body of the engine and the more quickly the engine heats up, the more quickly the oil in the device will be heated which, of course, acts to thin the oil and makes it flow more rapidly so that the device will work quicker after the engine has warmed up than it will when the engine is cool. The same effect will be caused by atmospheric temperatures as the colder the day, the more sluggish the oil will flow so that the choker will take a longer time to open on a cold day than it will on a warmer day. The time of opening of the choker valve can also be regulated by adjusting the parts through means of the nuts 18 and 19 and the spring 23.

It is thought from the foregoing description that the advantages and novel features of my invention will be readily apparent.

I desire it to be understood that I may make changes in the construction and in the com-

bination and arrangement of the several parts, provided that such changes fall within the scope of the appended claims.

What I claim is:

1. A choker device for an internal combustion engine comprising a cylinder connected with the choker valve, means for normally holding the cylinder in a position with the valve open, a choker rod for moving the cylinder to close the valve, a piston in the cylinder having its rod connected with a stationary part, fluid in the cylinder and valve means for permitting the fluid to pass by the piston when the cylinder is being moved upwardly but to prevent such movement when the cylinder is being moved downwardly.

2. A choker device for an internal combustion engine comprising a cylinder connected with the choker valve, means for normally holding the cylinder downwardly with the choker valve open, a choker rod connected with the cylinder for raising the same to close the valve, a hollow piston in the cylinder, a valve rod connected with the piston and passing through a stationary part, nuts on the valve rod for limiting its movement in the stationary part and to provide a specific partly open position of the choker, oil in the cylinder covering the piston, the ends of the piston having openings therein for the passage of the oil and an inwardly opening valve for closing the lower opening.

In testimony whereof I affix my signature.

ROBERT GALBRAITH RUSSELL.
